REFRIGERATION APPARATUS

Malcolm G. Shoemaker, Indianapolis, Ind., assignor to Westinghouse Electric & Manufacturing Company, East Pittsburgh, Pa., a corporation of Pennsylvania

Application March 24, 1939, Serial No. 263,838

8 Claims. (Cl. 62—3)

This invention relates to refrigerating apparatus and more especially to refrigerating apparatus employing a capillary impedance tube to retard the flow of refrigerant from the condenser to the evaporator.

In order to control the flow of refrigerant between the high pressure side of a refrigerating system, of which the condenser is a part, and the low pressure side, of which the evaporator is a part, a tube of considerable length and relatively small diameter, sometimes referred to as a "capillary tube" has been heretofore utilized.

One of the principal disadvantages of using a capillary tube for this purpose is that it depends primarily on the difference in pressure between the ends thereof for regulating the flow of refrigerant. It is, therefore, apparent that in a refrigerating system, for example of the type wherein the condenser is air-cooled and the evaporator is subjected to varying heat loads, as in the usual domestic refrigerator, the pressure drop across the tube varies considerably, with the result that the flow of liquid refrigerant through the tube changes.

Assuming for example, that the refrigerator is designed to operate in a room at a temperature of 80° F. and with a cabinet temperature normally maintained at 45° F. If the room temperature now increases, the condenser temperature and pressure will increase and will force an excessive amount of gas through the tube. Likewise, a decrease in cabinet air temperature with consequent decrease in evaporator pressure and decrease in amount of refrigerant pumped will result in an excessive amount of gas being forced through the capillary tube. This results in a loss of efficiency, since the gas is merely circulated through the system and reduces the usefulness of the work of the compressor.

If the temperature of the room decreases below 80° F. with subsequent decrease in condensing temperature, the amount of liquid refrigerant passed by the capillary tube will temporarily decrease and liquid refrigerant will back up into the condenser with consequent increase in condensing pressure above a value desirable at this room temperature. This will result in the loss in efficiency of the system and in addition the "pull-down" characteristics of the system, that is, the amount of time and work necessary to bring the cabinet down to the desired temperature are also deleteriously effected because the evaporator is starved and the machine is working less efficiently.

If the temperature of the air in the cabinet 55

increases above 45° F. with consequent increase in suction pressure, the amount of refrigerant pumped by the compressor will increase but the amount of liquid passed by the capillary tube will not increase sufficiently to take care of the increase in liquid pumped. This also results in starving the evaporator and increasing the discharge pressure with consequent loss in efficiency and undesirable effect on the pull-down characteristics of the system.

One object of the invention is to improve the efficiency of refrigerating systems utilizing constantly open flow restricting devices when operating under varying temperature conditions.

15 A further object is to combine a variable flow retarding device with a constantly open flow retarding device to increase the range of maximum efficiencies of refrigerating systems.

A further object of my invention is to pass refrigerant to the evaporator at such a rate that liquid refrigerant will not appreciably back up in the condenser nor will excessive amounts of gas be passed through the capillary tube.

These and other objects are effected by my invention as will be apparent from the following description and claims taken in accordance with the accompanying drawing, forming a part of this application, in which:

Fig. 1 is a diagrammatic view of refrigerating apparatus embodying my invention;

Fig. 2 is an enlarged sectional view of the variable flow retarding element of the apparatus; and,

Fig. 3 is a view of a modified form of the flow retarding element of the apparatus.

Referring specifically to the drawing for a detailed description of my invention, the numeral 11 designates a compressor which is driven by a motor 12 through a shaft 13. Refrigerant gas compressed by the compressor 11 is conveyed through a conduit 14 to a condenser 15, shown as an air-cooled condenser by way of example, wherein the compressed refrigerant gas is condensed by the cooling action of air forced through the condenser 15 by a fan 16. The condensed refrigerant is conveyed to an evaporator 17 wherein it vaporizes and withdraws heat from the air in an insulated compartment 18, whereupon the vaporized refrigerant is conveyed back to the compressor 11 through a conduit 19, and the cycle is repeated. An electrical control 21 controls the electric current supplied to the motor 12 from a source of electrical power 20, in response to the demands of the evaporator 17 for cooling. The motor runs at substantially con-

stant speed when operating. A suitable bulb 22 and a bellows 23 filled with an expansible fluid is associated with the evaporator 17 and is responsive to temperature variations thereof. The bellows 23 actuates a switch 24 of the over-travel type to open and close the contacts 25.

The flow of refrigerant from the condenser to the evaporator is controlled by a variable flow impeding device 26 and a capillary tube 27 connected in series therewith. The variable flow impeding device 26 comprises a cylindrical chamber 28 and a cylindrical body 29 located co-axially therein. A helical spring 31 having spaced apart convolutions occupies the space between the cylindrical body 29 and the cylindrical walls of the chamber 28. The spring 31 is somewhat longer than the cylindrical body 29 and is secured at its upper end 32 to the upper portion of the cylindrical body 29 and at its lower end 33 to the lower portion of the chamber 28. The cylindrical body 29 has a close working fit within the spring 31 and the spring 31 likewise has a close working fit with respect to the cylindrical chamber 28.

It will be apparent that this construction provides a helical passageway for the refrigerant between the convolutions of the spring 31, and that the cylindrical body 29 is adapted to move downwardly under the influence of a difference in pressure between its upper end and its lower end. This downward movement increases the length of the helical path which the refrigerant is forced to take in the cylindrical chamber 28 and also decreasing the cross-sectional area of this path by the compression of the spring 31. The end of the tube 27 projecting into the chamber 28 is cut at an angle to prevent the body 29, when in the lowest position, from blocking the tube 27. A small portion of the refrigerant will also flow across the convolutions of the spring 31 along the wall of the cylindrical chamber 28 because of the clearance space required between the movable parts of the variable flow impeding device 26.

The variable flow impeding device 26 is proportioned so that the cylindrical body 29 is in an intermediate position at some assumed average room temperature and at normal loading of the insulated compartment 18. If the temperature of the room in which the refrigerating apparatus is located increases above the assumed average temperature, the temperature of the condenser 15 will also increase and its pressure will increase correspondingly and tend to increase the flow of refrigerant through the flow impeding device 26. The increased pressure will also tend to decrease the rate at which the compressor 11 pumps the refrigerant vapor. The increased pressure at the upper end of the cylindrical body will cause this body to move downwardly and increase the flow impeding effect of the device as previously explained, thereby tending to hold the flow of refrigerant at the rate pumped by the compressor 11. The opposite action results if the temperature of the room drops below the average. The cylindrical body 29 will then rise and decrease the flow impeding effect of the device.

If, on the other hand, the temperature of the room remains constant and the insulated compartment 18 is loaded with warm supplies or the door (not shown) of this compartment is left open for a prolonged period, the temperature 70 of the evaporator 17 and correspondingly its pressure will increase thereby loading the compressor pump 11 more fully at each intake stroke so that a greater mass of the refrigerant vapor is withdrawn from the evaporator 17 than heretofore. 75

This operation would ordinarily result in the evaporator 17 being starved of refrigerant and the accumulation of the refrigerant liquid in the condenser 15. The increased pressure in the evaporator 17, however, reacts back through the capillary tube 27 on the lower portion of the cylindrical body 29 so that this body moves upwardly and a greater flow of refrigerant to the evaporator 17 takes place.

10 A somewhat similar effect is secured by the modification shown in Fig. 3. This modification also makes use of a capillary tube 27 but uses a seatless float valve 41 as the variable flow impeding device. The seatless float valve 41 comprises a chamber 42 communicating with both the condenser 15 and with the entrance end of the capillary tube 27. The float 43 in the chamber 42 is provided with a tapered needle 44 at its base and a tube 47 of tapered bore cooperating with the needle 44 to progressively restrict the flow of refrigerant from the condenser 15 to the tube 27 as the float 43 and the needle 44 descend. The lowermost position of the needle 44 provides the maximum added impedance likely to be desired in the usual operation of the refrigerating apparatus. The lowermost position of the needle 44, therefore, is not the entirely closed position of this variable flow impeding device. The upper position of the float 43 and the needle 44 is such that substantially no impedance is added to the impedance of the capillary tube 27.

15 The operation of the device is as follows:

During the normal operation of the refrigerator in a room of average temperature, the float 35 43 is supported in an intermediate position by the refrigerant in the chamber 42. If conditions arise which would ordinarily produce too rapid a flow of refrigerant through the capillary tube 27 such as an abnormally warm room temperature, the level of the refrigerant liquid in the chamber 42 is lowered, the float 43 descends and the tapered needle 44 enters farther into the tube 40 47 so that the refrigerant flow is held to a normal flow consistent with the pumping of the compressor 11.

45 If the conditions are such as to produce an abnormally low flow through the capillary tube 27, such as operating the refrigerator in a very cold room and loading the insulating compartment 18 with warm foods, the refrigerant level will rise in the chamber 42 and raise the float 43 together with the tapered needle 44 to decrease the impedance of the float valve 41 to the flow of refrigerant.

50 It will be apparent from the above that this invention provides a variable flow control device which together with the capillary tube impedes the flow of refrigerant to a varying degree and that this device increases the efficiency of a refrigerating system embodying a capillary tube. It will be further apparent that the variable flow impeding devices of this invention do not destroy the automatic unloading characteristic of the capillary tube because the devices are continuously open.

55 While I have shown my invention in several forms, it will be obvious to those skilled in the art that it is not so limited but is susceptible of various other changes and modifications without departing from the spirit thereof, and I desire, therefore, that only such limitations shall be placed thereupon as are imposed by the prior art or as are specifically set forth in the appended claims.

What I claim is:

1. In refrigerating apparatus, the combination of a compressor for pumping refrigerant, a condenser, an evaporator, and means for impeding the flow of refrigerant between the condenser and the evaporator, said means comprising a conduit of variable cross-sectional area, a movable body responsive to the pressure differential of the refrigerant across said body, said body controlling the conduit to vary its cross-sectional area to provide a flow varying substantially with the quantity of refrigerant pumped by said compressor regardless of the pressure differential between the condenser and the evaporator.

2. In a refrigerating system, the combination of a compressor, a condenser, an evaporator, a constantly open flow-impeding device having unvarying friction-producing surfaces, and a float valve, said float valve and said flow-impeding device being connected in series between the condenser and the evaporator, said float valve comprising a conduit having a continuously open elongated passage, a finely tapered needle projecting into said elongated passage, and a float controlling the position of said needle so that a relatively large movement of said float produces a relatively small change in the cross-sectional area of said passage.

3. In refrigerating apparatus, the combination of a compressor for pumping refrigerant, said compressor operating at substantially constant speed when active, a condenser, an evaporator, a constantly-open flow-impeding device having unvarying friction-producing surfaces, and a continuously open float valve connected in series with the flow-impeding device between the condenser and the evaporator, said float valve comprising a valve seat, a float, and a finely-tapered needle actuated by said float and closely fitting within but out of contact with at least portions of said valve seat so that a large movement of said float produces a relatively small change in the cross-sectional area between the needle and the valve seat.

4. In refrigerating apparatus, the combination of a compressor, a condenser, an evaporator, a flow-impeding device comprising a cylindrical chamber, a helical spring having spaced-apart convolutions in said chamber, said spring fitting closely against the interior cylindrical walls of said chamber, a cylindrical body within said spring and closely fitting the interior surface thereof, one end of said spring being secured to the cylindrical chamber adjacent one end thereof and the other end of said spring being secured to the cylindrical body, a constantly-open flow-impeding device having unvarying friction-producing surfaces connecting the evaporator and the portion of the cylindrical chamber adjacent the securing of the spring thereto, and a second conduit connecting the compressor to the portion of the cylindrical chamber adjacent the securing of the spring to the cylindrical body, said first-named flow-impeding device forming a variable restricted passage for refrigerant flowing therethrough.

5. In refrigerating apparatus, the combination of a periodically-operated compressor for pumping refrigerant, a condenser, an evaporator, a

constantly-open flow-impeding device having unvarying friction-producing surfaces, and a second flow-impeding device, said second flow-impeding device and said first-named flow-impeding device being connected in series between the condenser and the evaporator, said second flow-impeding device having a continuously-open elongated passage providing for unloading of the compressor between operating periods, said second flow-impeding device also including hydraulic friction-producing surfaces and a movable body in said flow-impeding device for varying the friction-producing surface of said elongated passage, so that said second flow-impeding device affords a substantially uniform flow of refrigerant through said first-named flow-impeding device when the compressor is operating corresponding substantially to that delivered by said compressor over the normal range of operating conditions of said apparatus, said movable body being responsive only to a condition of the refrigerant in said second flow-impeding device.

6. In refrigerating apparatus, the combination of a periodically-operated compressor for pumping refrigerant, a condenser, an evaporator, a constantly-open flow-impeding device having unvarying friction-producing surfaces, and a second flow-impeding device, said second flow-impeding device and said first-named flow-impeding device being connected in series between the condenser and the evaporator, said second flow-impeding device having a continuously-open elongated passage providing for unloading of the compressor between operating periods, said second flow-impeding device also including hydraulic friction-producing surfaces and a movable body in said second flow-impeding device for varying the friction-producing surface of said elongated passage, so that said second flow-impeding device affords substantially uniform flow of refrigerant through said first-named flow-impeding device when the compressor is operating corresponding substantially to that delivered by said compressor over the normal range of operating conditions of said apparatus.

7. In a flow-restricting device for refrigerating apparatus, the combination of a cylindrical chamber, a helical spring having spaced-apart convolutions in said chamber, said spring fitting closely adjacent the interior cylindrical wall of said chamber, and a cylindrical body within said spring and closely fitting the interior surface thereof, said body being of shorter length than said cylindrical chamber, said spring being secured adjacent one end to the cylindrical chamber and secured adjacent the other end to the cylindrical body, said cylindrical chamber having openings in its walls adjacent each end of said cylindrical body, and a constantly-open flow-impeding device having unvarying friction-producing surfaces communicating with one of said openings for connection in series with said cylindrical body.

8. The combination as claimed in claim 7 wherein the spring, when at rest, holds the cylindrical body within said spring with the unsecured end of the cylindrical body spaced from the secured end of the spring.

MALCOLM G. SHOEMAKER.
